UNITED STATES PATENT OFFICE

154,782

DESIGN FOR A VEHICLE

Otto F. F. Kiehn, Little Neck, N. Y.

Application December 31, 1947, Serial No. 143,473

Term of patent 7 years

(Cl. D14—3)

To all whom it may concern:

Be it known that I, Otto F. F. Kiehn, a citizen of the United States, residing at Little Neck, L. I., in the county of Queens and State of New York, have invented a new, original, and ornamental Design for a Vehicle, of which the following is a specification, reference being had to the accompanying drawing, forming part thereof.

I claim:

The ornamental design for a vehicle, as shown.

OTTO F. F. KIEHN.
